UNITED STATES PATENT OFFICE

AUGUST J. KLONECK, OF NEW YORK, N. Y.

RADIO APPARATUS

Application filed June 5, 1923. Serial No. 643,505.

The present invention relates to novel means and novel electrical circuits for amplifying high frequency signal currents.

One of the objects of the invention is to provide means for changing a low voltage direct current; such as from a storage battery or a low-frequency alternating current to a current of high voltage and frequency for operating the signaling circuits and apparatus.

Another object of the invention is to provide suitable means and circuits for increasing the amplification of received signal currents.

These and other allied objects are attained by a novel combination of means and electrical circuits hereinafter more fully described and shown in the accompanying drawing in which:—

20 The figure on the drawing illustrates a combination of novel means and of novel electrical circuits for a signal receiving system.

In the drawing, wherein like reference characters designate similar parts, the numeral 1 designates a rejector trap circuit including an inductance coil 16, a condenser 17 and a resistance 18. 10 is an aerial, 11 a ground. An antenna circuit includes the 25 aerial 10, a condenser 15, loading coil 14, and the primary coils 12 and 13. The numerals 23 and 24 designate tickler coils which are connected through a condenser 65 in the plate circuit of an electron tube 4. The numeral 22 represents an intermediately arranged filtering coil, tunable by a condenser 37 and serving for filtering the received signal current from the aerials for the receiving circuit. 21 is the secondary coil tunable by 30 a condenser 38. Upon the panel 30 are dials 33. A pinion 32 is secured to the dial 33 and engages a crown or bevel gear 31 of about four times its diameter. The gear 31 is rigidly connected with a coil socket 26 and turnably mounted in suitable brackets 27 and 28.

The latter are mounted upon said panel 30. Into the socket 26 fit suitable plugs 25 and 35, which latter carry preferably interchangeable coils as the coils 21 and 12—13 for instance. A non-rotatable socket 34

is shown in carrying the intermediate coil 22. The coils 12—23 and 13—24 are arranged with their magnetic fields opposing one another for preventing a reradiating of the received signals from the plate circuits. 55 They may be secured together by suitable strips 36 and attached to plug 35 in a manner so that only one of the primary coils 12 is more closely coupled or in a tighter inductive relation with the intermediate coil 22. Two 60 electron tubes 4 and 7 serve for amplifying a received signal current while an electron tube oscillator serves for supplying a high voltage plate current from a source of a lower voltage current. 65

The oscillating currents producing tube 5 comprises a plate electrode, a grid and a filament. The latter is energized by a battery 45 and has a terminal at an intermediate point thereof. The circuits of said electron tube 5 comprising a low voltage plate battery 46 connected with one terminal to the filament and with the other terminal in multiple to two coils 47 and 49 of a transformer 48 which latter substitutes for the usual impedance coupled circuit so as to permit the use of a low resistance shunt circuit across the oscillator 5. Coil 47 is connected to the plate electrode of the oscillating currents producing tube 5. The other coil 49 forms an oscillation circuit in multiple to the oscillating currents producing tube and comprises a condenser 50, a primary coil of a voltage increasing transformer 52 and to the filament 70 and other terminal of said battery 46. The transformer 48 serves for producing forced inductive reactions between the oscillation circuit and the discharges through the plate electrode of said tube 5 while in the present 75 practice of impedance coupling, as for instance by connecting the bypass condenser 50 to the plate directly, the high impedance which is necessary in the plate circuit would permit only a feeble current to pass through its high resistance circuit and thus it would operate a coupling means like the coil 52 with insufficient power. 80

The secondary coil 53 of transformer 52 has an intermediate terminal connected through a coil 54 of the oscillation controlling 85

100

transformer 55 to the intermediate terminal of the filament of the electron tubes 4 and 5. Other terminals of coil 53 serve for obtaining different high potentials for the plate circuits of the electron tubes 4 and 7 and also a negative potential for the grid circuits of said electron tubes. The grid of tube 5 is controlled by a coil 56 of transformer 55 which connects to a terminal of coil 53 of a negative potential for the grid of oscillator tube 5. The arrangement of the transformer coils 54 and 56 is such that if no current flows through the positive side of coil 53, then the current which flows through the negative side of coil 53 through the intermediate terminal predominates in flowing through coil 54 and produces a negative energization of the grid circuit as shown by the dotted line arrows and thus prevents a flow of a large current through the plate circuit and a corresponding decrease of current through the primary coil of transformer 52. But if a current from the positive side of coil 53 is drawn for utilization by the receiving circuits, then a current, flowing in an opposite direction as shown by the full line arrows acts through coil 54 upon coil 56 and the grid circuit for producing a more positive grid swing which permits a larger current flow through the plate circuit and the cooperating primary coil of transformer 52 proportionally, and thus regulating a flow of the primary current according to the demand of a secondary current from coil 53. The electron tube oscillations are preferably adjusted to a higher frequency with respect to that of the receiving circuit so that the secondary currents from coil 53 will be modulated by the received signal currents and in turn heterodyned or autodyned by the oscillations set up by transformer 3.

The electron tube 4 serves for amplifying radio and audio frequency currents. Its grid circuit comprises an audio transformer 66, having its secondary shunted by a condenser 43, further said secondary coil 21 of the aerial coupling system, then through a rotor coil 40 of an inductance 3 to a terminal at the negative side of coil 53 and then through coil 54 to the intermediate terminal of its filament.

The plate circuit of electron tube 4 leads through the primary coils of transformer 66 and suitable inductance elements or a choke 55 coil toward resistance 59 and in multiple thereof from the plate of the electron tube 4 through the tickler coils 23 and 24 and tuning condenser 65 and further toward resistance 59, then through a low frequency transformer 58 and through a coil 42 toward a terminal of high potential of the current supplying transformer coil 53 and through coil 54 to the filament of the electron tube 4. In multiple connected to the resistance 59 is a low resistance circuit including a bypass condenser 61

in series with the primary 64 of transformer 6 toward an intermediate terminal of transformer 58.

The purpose of the condenser 61 in series with the primary of transformer 6 is to prevent a flow of current through the latter when no signals are received while the reactive transformer 58 produces an increased reaction or amplification of signals.

The electron tube 7 has its grid connected in series with the secondary coils 62 and 63 of transformer 6, then through a rotor coil 69 of transformer 8 which latter serves for opposing tube oscillations to a selective switch; and from the lowest switch point of said switch to a negative terminal of coil 53 and through coil 54. An intermediate terminal of said switch connects coil 69 and the grid circuit of electron tube 7 in multiple to the plate of electron tube 4 by means of said coupling transformer 58. A bypass condenser 44 is connected in the plate circuit of electron tube 4. Other bypass condensers may be used as convenient.

The electron tube 7 embodies a novel construction. It will be noted that the position of the so-called plate in electron tube 7 is not dependent upon the usual position farthest from the filament. By covering the farthest from the filament arranged electrodes of tube 7 with an amalgam of caesium, rubidium and potassium, then we obtain a photoelectric cell wherein the light from the filament merely serves for making the space between the electrodes thereof conductive.

The electron tube 7 shows three grid elements arranged successively between a filament and a plate electrode. The nearest to the filament arranged element shown as a grid is connected to the filament or to the negative terminal of coil 53. The second and fourth electrode elements from the filament serve for the positive and negative element of this discharge device which in this case operates as a photoelectric tube. A high potential current from the 100 volt terminal of coil 53 is connected through a coil 72 of the oscillation counteracting transformer 8 to two coil parts 73 and 74 of a reactive transformer 75 to the second and fourth elements of tube 7. The coil 74 includes a receiving instrument 77 connected in series therewith. The third element from the filament serves for the well known grid purpose of acting as a stopper or valve for the discharges of current between the other elements. In the case of tube 7 acting as a photoelectric cell, its filament consists of an iron or tungsten alloy which discharge ultraviolet rays if heated by suitable means. In this case, furthermore, the filament should preferably be energized separately from the other elements, so as to prevent a discharge from them as a plate serving element toward the filament.

The transformers 3 and 8 although of simi-

lar construction serve for different purposes depending upon the direction of current surging through coils 40 and 69, when energized by currents from coils 42 and 72 or 41 in one or 5 the other direction. In the case of transformer 3, its rotor coil 40 produces an energization or regeneration upon the grid in a direction which supports a discharge of current from the plate and thus makes the electron tube 4 oscillating at a high frequency depending upon the adjustment of the constants thereof. The circuits of transformer 3 are so proportioned that they co-act to produce oscillation at any beat frequency or preferably, 10 at a multiple of a higher frequency or shorter wave than that of the signal current and preferably of a frequency near to that of the current supplying transformer 53. The transformer 8 however has its rotor coil 69 15 in an opposed direction adjusted for neutralizing a tendency of the tube toward self oscillating. The coil 41 hereby serves for producing a magnetic field or an energization toward a saturation of the transformers 3 and 20 8, while a flow of current through the plate coils 42-72 or the grid coils 40-69 will produce a disturbing effect upon the magnetic field from coils 41 which in turn will react upon the coils from the grid and plate circuits. 25

The coupling transformers, for instance transformer 58 is connected in the circuit where the circuit parts to two branches. The purpose of the transformers of this type is to 30 produce forced co-actions between the two branches of the circuit.

The purpose of employing two tickler coils 23 and 24 is to arrange the same for preventing reradiation by producing opposing currents and no resultant currents from the primaries or aerial coils 12 and 13 of the aerial 35 circuit since the plate coils 23-24 will produce opposite and thus no resultant voltage in the coils of the aerial circuits. One of the 40 coils 24 for instance, is wound in an opposite direction with respect to coil 13 and arranged separately or adjacent which latter are not coupled to the secondary circuits the coupling coils including the primary 12, and the 45 tickler 23 for the secondary 21.

A novel means for producing a transformer with similar impedance values but different number of turns for the primary and secondary coils is employed in connection with 50 transformers 6 and 66. The secondary coils 62 and 63 of transformer 6 for instance, are wound on cores of small cross section with a certain number of turns. Several of such secondary coil cores according to the ratio of 55 turns as desired between primary and secondary are then arranged parallel to a single core cross section and wound with the primary coil 64 of the same number of turns as one of the secondary coil sections. In this case then 60 the cross section of the core of the secondary

coils will be that of one coil while the primary coil will have as a core all the cores of said secondary coils.

Another novel means is employed for preventing a burning out of the insulation of the transformer coils. For this purpose the wire for said coils which may be blank, enamelled or cotton covered are drawn through soluble silicate and then through a fine powder consisting of gypsum, clay, sand or glass for receiving a fireproof coat. Or a wet wire is drawn through powdered cement or a coat of silicate is dried on the wire and the wire passed through acid, calcium carbonate, calcium sulfate for producing a coat of insoluble silicate on the wire. Such prepared insulation will permit a heating of the transformer by heavy currents but prevent a damage to the transformer. By employing the necessary compounds for the insulation then 65 a heating of the transformer will produce a glass or a porcelain structure of such transformer.

The operation of the system is as follows:—A signal received by the aerial-ground connection flows through the primary 12 and by the latter energizing the secondary coil 21 through an intermediate filtering reactance 22-37. The secondary currents operate the grid of tube 4 in the usual manner. 70 A regeneration of the signal is obtained through the tickler coil 23 by a variable coupling or by a condenser adjustment 65 or both. The electron tube 4 acts now as a detector and a regenerator. The plate circuit of 75 said tube includes the primary of a transformer 6 and a low resistance part of the audio reactance 58 for permitting a large current flow and in multiple thereof through a circuit of high resistance 59. The electron tube 4 having as well known the capacity of a rectifier in that it permits current to flow in one direction only acts also as a rectifier for other high frequency currents. The primary of another audio transformer 66 is connected 80 in series with the plate of the electron tube 4 and in multiple to the primary of the audio transformer 66 is a radio frequency coil 23 or the tickler coils 23 and 24 in series with a bypass condenser 65. The amount of currents bypassed by the shunted condenser circuit is larger with a larger capacity condenser. When a detector tube is oscillating then a grid stopping condenser for obtaining 85 rectification of high frequency currents may be omitted, similarly a tube connected as in a reflex circuit rectifies a portion of the high frequency currents.

In this case the secondary of transformer 66 is connected to the grid circuit to permit a certain amount of increased audio amplification. Some electron tubes permit a variation of the amplification by a variation of the filament rheostat.

The adjustment of the high frequency os- 90

cillation producing circuit 40, 42 serves best to keep the tube near the point where oscillations and signal current are nearly equal in power.

5 The high frequency plate current producing oscillator tube 5 is controlled by way of the secondary coil in a manner so that an increased secondary current drawn to the other tubes produces a more positive grid and thus 10 greater reactions from the plate coil 47 upon the currents flowing through coil 49 in the low resistance circuit including the primary of the transformer 52, 53.

15 The grid of the amplifying tube 7 is connectable through the secondary coils 62 and 63 to the filament or negative transformer terminal respectively or also in series as a 20 step up ratio impedance to the coupling transformer 58.

25 It will be noted that the combination of the described circuits and elements will produce a device of improved character.

What is claimed is:—

1. In a signaling system the combination 25 with receiving circuits and cooperating elements, of a plurality of electron tubes including operating electrodes, input and output circuits, a voltage supplying transformer for operating certain of said electron tubes for 30 amplifying signals by means of a high frequency current therefrom, a source of current, said electron tubes including an oscillator, said transformer having primary and secondary coils, said primary being in connection with said source of current and with said oscillator, means for producing reactions of 35 said oscillator of a frequency preferably above the range of frequencies of a received signal current but not necessarily at a higher 40 harmonic of a signal current, said reactions of said oscillator energizing said primary of said transformer and by the latter said secondary, the latter having a plurality of different voltage terminals for operating said 45 amplifying electron tubes at any desired voltage, said amplifying electron tubes having output circuits operating at different frequencies regardless of the operating high frequency current from said oscillator and 50 transformer by conventionally bypassing the higher frequency currents in said output circuits.

55 2. In a signaling system the combination with receiving circuits and cooperating elements, of a plurality of electron tubes, having output circuits, and being adapted to amplify a received signal current, a transformer for supplying a high frequency current for said output circuits of said electron tubes at a desired voltage, an oscillator 60 electron tube serving for operating said transformer, a source of current for operating said oscillator tube and transformer for producing a high voltage current for the output circuits of said amplifying electron tubes, and

means for operating said output circuits at a lower frequency than the frequency of said generated operating current.

3. In a signaling system the combination with electric circuits, of a source of current, 70 a voltage transformer including a primary and secondary, the latter including a plurality of terminals for obtaining different voltage values and polarities, including a terminal between coil parts of opposed polarities of said secondary of said voltage transformer, an electron discharge tube adapted for supplying a plate current of an independent high frequency to other electron tubes and utilizing means including plate, grid and space 80 conductivity producing electrodes, said circuits including said source of current, said primary, a tuning condenser and said discharge tube, a second transformer having one coil thereof connected between said terminal 85 between said coil parts of said secondary and said conductivity producing electrode, another coil of said second mentioned transformer having one terminal connected to a terminal of negative polarity of said secondary coil parts and its other terminal to the grid electrode of said discharge tube for the purpose as set forth.

4. In a signaling system the combination 95 with an electric circuit, of an electron tube including electrodes for discharging a current through the space therebetween, a grid adapted for modifying a discharge and means for ionizing the space between said electrodes, a source of current adapted for supplying 100 energy for the operation of said electron tube, a voltage transformer having a primary and secondary, the latter having a plurality of terminals for tapping different current values from said secondary, means for employing a point intermediate of the secondary coil parts as a zero terminal for a utilizing circuit, a reactive transformer, means for connecting said source of current to said discharge electrodes of said electron tube in series with a 110 coil of said reactive transformer, and a circuit including a second coil of said reactive transformer connected between said first mentioned coil and one terminal of said source of current and through a condenser and the primary of said transformer to the other terminal of said source of current, and means for 115 operatively modifying an energization of said grid electrode for producing high frequency oscillation in said transformer through said discharge tube.

5. In a signaling system the combination 125 with electric circuits, a source of current, a plurality of electron tubes including a plurality of electrodes, means for operating said circuits by a high frequency plate current supply, a coupling transformer for said electron tubes, said transformer having primary and secondary coils and cores, means for arranging one set of said coils of said transformer 130

upon parallel cores, means for utilizing said parallel cores of said mentioned coil set as a single core for the other coil of said transformer, and means for operatively connecting said source of current, said transformer coils and said electron tubes for the purpose set forth.

6. In a signaling system the combination of electric circuits including an electron discharge device having a plurality of electrodes, means for causing a discharge between said electrodes, a source of current, a signal responsive device connected between said source of current and said discharge device including two of said electrodes and a coil of a high frequency transformer, a primary circuit and means for receiving electrical signal current arranged in an operative relation with said discharge device including one of said two electrodes and a third electrode and another high frequency coil in an operative relation with said first mentioned high frequency coil and means for producing electrical oscillations in said circuits at an independent higher frequency than that of the received signal carrier frequency including said high frequency coils, and suitable elements for amplifying the currents in said circuits.

30 7. In a signaling system the combination, of electric circuits including a plurality of discharge devices, the latter having input and output circuits, a source of current connected with said output circuits and an auto transformer having two coil parts, means for connecting one of said coil parts to an output circuit including said source of current, and means for connecting the other coil part to a tunable circuit at the frequency of the signal current, and means for connecting said tunable circuit with the input side of one of said discharge devices.

8. In a signaling system the combination with electric circuits, of a discharge device having a plurality of electrodes and means for causing a discharge of current between said electrodes, said electrodes including a plurality of grid electrodes, said discharge device including input and output circuits, a source of current connected with said output circuit, an auto transformer having an intermediate terminal connected with said source of current, a plate electrode and a receiving device for signals connected with one end of said auto transformer, and one of said grid electrodes connected with the other end of said auto transformer.

9. A signaling circuit including electron tubes for amplifying radio and audio frequency currents, of circuits and suitable elements for operating the same including the primary of an audio transformer, of circuit connections, between said elements and one of said electron tubes including two branch circuits connected in multiple, one of said

branch circuits including a radio frequency amplifying coil connected in series with a condenser, the other branch circuit including said primary of said audio frequency transformer, all for the purpose of permitting each of said multiple connected elements and circuits to operate at their particular frequency.

10. In a signaling system the combination with electron tubes for amplifying signals including conventionally used circuits and elements for operating the same including an output circuit and an element for utilizing an amplified signal, an auto transformer and a source of current connected to said output circuit forming a circuit of high resistance, and a condenser connected in series with said element for utilizing an amplified signal, said source of current and a terminal of said auto transformer forming a circuit of low resistance for currents from said mentioned source adapted to be modulated by signals from said mentioned operating circuits.

11. In a signaling system the combination with electron tubes, of an aerial circuit including two primary coil parts, an electron tube thereof having an input circuit and a regenerative output circuit, said input and output circuits including coils and condensers, coupling means for associating said input circuit with one of said coil parts of said aerial circuit, said two coil parts of said aerial circuit being separated from each other sufficiently, said output circuit including coil parts in an inductive connection with both of said aerial coil parts, but in a manner so that the coil turns of said two aerial coil parts are opposed to the coil turns of said coil of the regenerative output circuit for preventing reradiation of received signals.

12. In a signaling system, an aerial circuit including two terminals, a local signaling circuit including a coupling coil, for said aerial circuit, a tuning condenser, an inductance and a coupling coil toward said local circuit connected in series with one another and between said two aerial circuit terminals, a tuning inductance shunted by a tuning condenser connected additionally between said two aerial terminals including means for changing the tuning range of said last mentioned tuning means.

In testimony whereof, I have signed my name to this specification this 31st day of May, 1923.

AUGUST J. KLONECK.
